US0D1028897S

(12) **United States Design Patent** (10) Patent No.: **US D1,028,897 S**
(45) Date of Patent: ** May 28, 2024

(54) **CONNECTOR**

(71) Applicant: **Molex, LLC**, Lisle, IL (US)

(72) Inventors: **Ravikanth Desai**, Bengaluru (IN);
Rahul Bhaskar, Bengaluru (IN);
Narayan Mithun, Bengaluru (IN);
Kalidindi Ramesh Raju, Bengaluru (IN);
Debashis Sarkar, Bengaluru (IN)

(73) Assignee: **Molex, LLC**, Lisle, IL (US)

(**) Term: **15 Years**

(21) Appl. No.: **29/753,394**

(22) Filed: **Sep. 30, 2020**

(51) LOC (14) Cl. **13-03**

(52) U.S. Cl.

USPC **D13/133; D13/147**

(58) **Field of Classification Search**

USPC D13/101, 107, 118, 123, 133, 138.2,
D13/146-147, 149, 153-154, 156, 173,
D13/184, 199; D14/256, 433

CPC G02B 6/3879; G02B 6/3893; G02B
6/38875; H01R 13/6275; H01R 13/6392

See application file for complete search history.

(57) **CLAIM**

The ornamental design for a connector, as shown and described.

DESCRIPTION

FIG. 1 is a rear top perspective view of a connector showing our new design;

FIG. 2 is a front top perspective view thereof;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a front view thereof.

The broken lines immediately adjacent to the shaded area represent the bounds of the claimed design and form no part thereof. The broken lines depicting the remainder of the connector form no part of the claimed design.

1 Claim, 8 Drawing Sheets
